Patented Nov. 28, 1972

225,200

REFRIGERATED SHOW CASE

Tony J. Bressickello, 13015 S. Normandie Blvd.,
Gardena, Calif. 90249

Filed Oct. 8, 1970, Ser. No. 25,392

Term of patent 14 years

Int. Cl. D6—06

U.S. Cl. D6—172

FIG. 2

FIG. 3

FIG. 4

FIG. 1

FIG. 5

FIG. 6

FIG. 7

FIG. 1 is a perspective view of a refrigerated show case, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof.

I claim:

The ornamental design for a refrigerated show case, substantially as shown.
